(57) **CLAIM**

The ornamental design for a container for pouches of smokeless tobacco, as shown and described.

DESCRIPTION

FIG. 1 is a perspective view of a container for pouches of smokeless tobacco, according to our new design, wherein the lid and base are separated;

FIG. 2 is a top plan view of the base portion thereof;

FIG. 3 is a side elevational view thereof, wherein the base and lid are separated;

FIG. 4 is a side elevational view thereof wherein the base and lid are shown in the closed configuration;

FIG. 5 is a second top plan view of FIG. 2, showing unclaimed environmental structure;

FIG. 6 is a perspective view of a container for pouches of smokeless tobacco, according to a further aspect of our new design, wherein the lid and base are separated;

FIG. 7 is a top plan view of the base portion thereof;

FIG. 8 is a side elevational view thereof, wherein the base and lid are separated;

FIG. 9 is a side elevational view thereof wherein the base and lid are shown in the closed configuration; and,

FIG. 10 is a second top plan view of FIG. 7, showing unclaimed environmental structure.

The broken lines in FIGS. 5 and 10 showing pouches of smokeless tobacco in the containers is included for the purpose of illustrating unclaimed subject matter only and forms no part of the claimed design.
